United States Patent Office.

FRANKLIN A. WELLS, OF BRATTLEBORO, VERMONT, ASSIGNOR TO JACOB ESTEY AND COMPANY, OF SAME PLACE.

Letters Patent No. 76,013, dated March 24, 1868.

IMPROVEMENT IN REED-ORGANS.

The Schedule referred to in these Letters Patent and making part of the same.

TO ALL PERSONS TO WHOM THESE PRESENTS MAY COME:

Be it known that I, FRANKLIN A. WELLS, of Brattleboro, of the county of Windham, and State of Vermont, have made a new and useful invention having reference to Reed-Organs or other musical instruments of like character; and do hereby declare the same to be fully described in the following specification, and represented in the accompanying drawings, of which—

Figure 1 denotes a top view,

Figure 2 a front elevation, and

Figure 3 a transverse section of a reed-organ swell with my invention applied to it.

The purpose of my invention is to enable a performer or person to readily move and adjust the knee-bearer of the swell to a convenient position for being worked by his or her knee, while he or she may be playing the reed-instrument. My invention also insures the maintenance of the bearer in such position, while it may be desirable to there preserve it.

In the drawings, A denotes a part of the frame of a reed organ, *a* being the board or base, on which the system of reeds is arranged. B is the reed-case or carrier, and C the swell or swell-board, which is hinged or applied to such reed-carrier in the ordinary manner. A spring, D, bearing on a stud, *b*, extending from one end of the swell, serves to force the swell downward or to close it. Another stud, *c*, is extended from the swell, in manner as shown in the drawings, and over and upon an arm, *d*; projected from a rocker-shaft, *e*. A crank, *f*, extending down from one end of the rocker-shaft, is connected with a horizontal lever, *E*, by a connection-rod, *g*. The rod should be so applied to the crank and lever as to enable the latter, while being moved aside, to move the crank in a manner to cause the shaft to turn, and, by means of its arm and the stud *c*, effect the elevation of the swell. The lever *E* extends underneath the board *a*, the fulcrum *h* of the lever being at or near its rear end, and projected from the board.

The knee-bearer *F* is not in one piece with the lever, but is a piece separate therefrom, and is arranged against one side of the lever, and turns vertically on a screw, *k*, which goes through the bearer, and is screwed into the lever. The rear end of the bearer is rounded or formed as shown in fig. 3, and it has a friction-brake or spring, *l*, bearing against it, such spring being fastened to the lever *E*. This spring or brake serves to hold the knee-bearer in any position to which it may be moved vertically. The separate bearer, applied to the lever in manner substantially as described, can be easily adjusted to a convenient height for the knee of the player of the instrument or reed-organ to bear against it, in order to enable the knee to actuate the lever *E*, for the purpose of opening the swell. The spring, by its pressure and friction on the rear or curved end of the bearer, is caused to perform the function of retaining the bearer at such height.

The adjustable knee-bearer, combined with the lever, enables such lever to be operated as well by a child as by an adult, or to be brought readily into the most convenient position to be worked by any performer while playing the instrument.

What I claim as my invention is as follows:

The combination and arrangement of the friction-spring or brake, with the adjustable knee-piece and lever *E* of the mechanism for effecting the elevation of the swell.

FRANKLIN A. WELLS.
